No. 876,255.

PATENTED JAN. 7, 1908.

H. G. BENTLEY.
SELF LOCKING SEAL.
APPLICATION FILED JULY 25, 1907.

UNITED STATES PATENT OFFICE.

HORACE G. BENTLEY, OF DENVER, COLORADO.

SELF-LOCKING SEAL.

No. 876,255.

Specification of Letters Patent.

Patented Jan. 7, 1908.

Application filed July 25, 1907. Serial No. 385,545.

To all whom it may concern:

Be it known that I, HORACE G. BENTLEY, a citizen of the United States, residing at Denver, in the county of Denver and State of Colorado, have invented certain new and useful Improvements in Self-Locking Seals; and I do hereby declare the following to be a full, clear, and exact description of the invention, such as will enable others skilled in the art to which it appertains to make and use same, reference being had to the accompanying drawings, and to letters and figures of reference marked thereon, which form a part of this specification.

15 This invention relates to new and useful improvements in automatically locking seals and comprises various details of construction and combinations and arrangements of parts which will be hereinafter fully described and 20 then specifically defined in the appended claims.

My invention is illustrated in the accompanying drawings which, with the letters of reference marked thereon, form a part of the 25 application, and in which:

Figure 1 is a perspective view of my improved seal, showing one end inserted and held within a suitable casing. Fig. 2 is a sectional view on line 2—2 of Fig. 1. Fig. 3 30 is a sectional view showing both ends of the securing strap fastened within the casing. Fig. 4 is a perspective view showing the parts of the lock disassembled. Fig. 5 is a detail view showing in perspective the end of 35 the seal strap which is attached to the casing, and Fig. 6 is a detail view of the strap showing a wing at the end thereof, which is adapted to be folded in the manner shown in Fig. 5 of the drawings.

40 Reference now being had to the details of the drawings by letter, A designates a securing strap made preferably of any suitable metal and provided with an opening a near one end thereof, and B designates a hollow 45 casing or chamber made of two sections which are fastened together by the marginal edges thereof being interlocked in any suitable manner. One of said sections of the casing is provided with an aperture C 50 formed in the flange thereof and is adapted to receive the hooked end D of said strap A, in the manner clearly shown in Figs. 2 and 3 of the drawings. It will be understood that the end D of the strap A is inserted through 5 the opening C before the two sections of the casing are fastened together and, when once

inserted in place, the marginal edge of one of the sections of the casing is clenched over the end D whereby the latter may be securely held in place. Referring to Figs. 4 to 60 6 inclusive of the drawings, it will be noted that said strap A has a wing A' near one end thereof, which is adapted to be folded over upon the strap, and said wing is provided with an aperture E which, when folded as shown in Fig. 5, is in registration with an aperture E' in the shank of said strap. Said wing also has a resilient finger F at one end thereof with a space intervening between the same and the portion of said wing which is perforated. 70 Near the end of the strap A is an opening H, and K designates a recess or indented portion of the strap continuous with the forward marginal edge of the opening H and provided for the purpose which will be hereinafter 75 described.

N designates a resilient locking member made preferably of a bar of spring steel and one end of which is bent as at N' at right angles and adapted to rest upon the bottom 80 of the indenture K upon which it is movable, and the shank portion of said locking member N is sprung underneath the resilient finger F, which latter holds said member with sufficient frictional force in an adjusted 85 position. The opposite end of said member N is provided with an angled portion O which rests, when the device is set to receive the free end of the strap, upon the outer surface of the wing A'. 90

One of the sections of the casing, it will be noted, has a cut-away portion Q, shown clearly in Fig. 4 of the drawings, which is provided to allow one end of the wing A' to extend therethrough. It will be observed 95 that the wing A' is spaced apart from the strap proper against which it is bent a sufficient distance to allow the free end of the strap to be inserted between said wing and the outer face of the strap. After the parts 100 have been assembled by the locking member N being secured underneath the finger F and held in the position shown in Fig. 4 of the drawings and the end of the strap D passed through the opening C in the lower section of 105 the shell and the two sections of the shell secured together, the seal is in readiness to be locked. When it is desired to lock the free end of the strap A within the casing, 110 said end is inserted between the wing and the shank of the strap and, coming in contact with the inner angled end of the member N

2

a further inserting movement of said free end, will cause the member N to move therewith and, after the opposite angled end O passes over the marginal edges of the two 5 registering apertures E and E' in said strap and wing, said end O will spring through the apertures and also the aperture a, which is formed near the end of the strap A, thereby securely holding the end of the strap from 10 being withdrawn by said angled portion O coming in contact with the marginal edges of the three apertures E, a and E', as will be readily understood. Pulling upon the free end of the strap, will cause the locking member N to be drawn slightly in one direction and, when the end N' passes off the indented portion K, said end N' will spring through the aperture H in the strap and will co-operate with the angled portion O to securely 15 hold said member N in a locking relation.

As the space intermediate the wing and the shank portion of the strap is only of sufficient width to allow the insertion of the free end of the strap and as the opening in the marginal edge of one of the sections forming the 25 casing is only of sufficient dimension to allow the parts of the strap to project therethrough, it will be observed that any tampering with the seal by the use of instruments in an attempt to disconnect the ends will be practically impossible without first destroying the casing.

By the provision of a seal embodying the features set forth, a simple and efficient device is afforded in which the parts utilized are 35 reduced to a minimum and one in which a secure lock is afforded.

What I claim to be new is:—

1. A self locking seal comprising a casing, 40 a strap attached firmly thereto and provided with an aperture, said strap having a wing provided with an aperture in registration with an aperture in the strap, a flat longitudinally sliding resilient locking member 45 having angled ends resting one upon the outer face of said wing and the other against the adjacent face of the strap, one of said angled ends adapted to be moved by the insertion of the locking member to swing 50 through registering apertures in the strap

and wing, and an integral finger upon the wing adapted to bear against said sliding locking member, as set forth.

2. A self-locking seal comprising a casing, 55 a strap attached firmly thereto and provided with an aperture, said strap having a wing provided with an aperture in registration with the aperture in said strap, a longitudinally sliding resilient locking member having angled ends adapted to rest one upon 60 the outer face of the wing and the other upon the face of the strap adjacent to its fixed end, said wing provided with an integral resilient finger bearing against and adapted to engage and hold said locking member in a bowed 65 position, so that one of the angled ends of the member may be in the path of the inserted end of the strap, said member being adapted to be moved longitudinally by the inserted end of the strap and one of its 7 angled ends thrown through an aperture in the strap by said integral projection of the wing, as set forth.

3. A self-locking seal comprising a casing, a strap attached firmly thereto and provided with an aperture, said strap having a wing provided with an aperture in registration with the aperture in said strap, a longitudinally sliding resilient locking member having angled ends adapted to rest one upon the outer face of the wing and the other resting in an indenture formed in the strap adjacent to its fixed end, said indenture leading into an aperture formed in the strap, said wing provided with an integral resilient finger adapted to bear against said member and hold the same under tension, the inner angled end resting in said indenture being positioned in the path of the inserted end of the strap and adapted to be moved thereby, the angled ends of the locking member adapted to be thrown into apertures in the wing and strap when in registration with said aperture, as set forth.

In testimony whereof I hereunto affix my signature in the presence of two witnesses.

HORACE G. BENTLEY.
